(57) CLAIM

The ornamental design for a pointed toe shoe with heel and outsole patch, as shown and described.

DESCRIPTION

FIG. 1 is a perspective view of an embodiment of my new design of a pointed toe shoe with heel and outsole patch; FIG. 2 is a first side view of the design of FIG. 1; FIG. 3 is a second side view of the design of FIG. 1; FIG. 4 is a top view of the design of FIG. 1; FIG. 5 is a bottom view of the design of FIG. 1; FIG. 6 is a front view of the design of FIG. 1; and, FIG. 7 is a back view of the design of FIG. 1. The broken lines illustrate features of the shoe that form no part of the claimed design.
